(57) **CLAIM**

The ornamental design for an airplane, as shown and described.

DESCRIPTION

FIG. 1 is a perspective view of the first embodiment of an airplane, showing our new design;

FIG. 2 is a side view thereof;

FIG. 3 is a top view thereof;

FIG. 4 is a front view thereof;

FIG. 5 is a perspective of the second embodiment of an airplane;

FIG. 6 is a side view thereof;

FIG. 7 is a top view thereof; and,

FIG. 8 is a front view thereof.

Broken lines shown in the drawings illustrate inner portions of the engines that form no part of the claimed design.
